UNITED STATES PATENT OFFICE.

FREEBORN F. RAYMOND, 2d, OF NEWTON, MASSACHUSETTS.

NAIL MAKING AND DISTRIBUTING MACHINE.

SPECIFICATION forming part of Letters Patent No. 380,596, dated April 3, 1883.

Application filed October 27, 1887. Serial No. 253,484. (No model.)

To all whom it may concern:

Be it known that I, FREEBORN F. RAYMOND, 2d, of Newton, in the county of Middlesex and State of Massachusetts, a citizen of the 5 United States, have invented a new and useful Improvement in Nail Making and Distributing Machines, of which the following is a full, clear, and exact description, reference being had to the accompanying drawings, forming a 10 part of this specification, in explaining its nature, in which—

Figure 1 is a view in side elevation of the machine. Fig. 2 is a view in rear elevation, a portion of the machine being broken out to 15 represent the operation of the throat-clearing device, hereinafter described. Fig. 3 is a vertical section of the machine. Fig. 4 is a plan view of the pattern-plate for holding the tube ends, hereinafter referred to. Fig. 5 is a view 20 in horizontal section and plan upon a line over the ratchet-wheel upon the nail-holder. Figs. 6 and 7 are detail views. Fig. 8 is a view in perspective of the nail-receiving block and distributor.

25 This invention may be called an improvement upon that described in the application of Chester C. Small for patent for improvement in nail making and distributing machines, filed April 21, 1887, Serial No. 235,648, 30 the nail-making devices being substantially identical with those therein described, and comprising a roll, A, having a box-pointing die, a, a roll, A', having a nail-pointing die, a', a shaft, a², supporting the roll A, the shaft 35 a³, supporting the roll A', (which shafts are geared together,) the wire-feed rolls B B', and the nail-cutters C C', operated by the cam or abutment c, as described in said patent application. The feed-rolls are also operated substantially as therein described—namely, by a 40 ratchet-wheel, b, upon the shaft of one of the rolls, the pawl b', arranged to engage the teeth of the ratchet-wheel, mounted upon a swinging arm b², which is pivoted at b³ and is oscillated by a crank, b⁴, on the roll-shaft a², and the connecting-rod b⁵.

45 D is the throat or passage through which the nails are delivered from the nail-making devices to the nail-distributer. The nail-distributer comprises a nail-holder, E, having a series of nail-receiving holes, e, located in a circular order or arrangement at a uniform dis-

tance apart. (See Fig. 8.) The nail-holder E also has the central hole, e', which fits on the stationary stud e², which forms a bearing 55 for it. The block also has a nail-hole-covering plate, e³, which has perforations e⁴, and which is adapted to be moved to cover and uncover the holes e. This plate is attached to the holder E, to be rotated therewith, and is 60 moved at the end of the rotation of the block both to uncover and to cover the nail-holes. The holder also rests upon the circular bed e⁵, extending from the stud e², preferably integral therewith, although not essentially so. 65 The holder E also has the ratchet-teeth e⁶ formed upon or in its exterior surface near the lower end, or, preferably, in a ring or wheel fitted to said surface. The block is provided with intermittent periods of rotation and rest 70 by means of a feed-pawl, e⁷, (see Fig. 5,) which is carried by a slide, e⁸, arranged to move in the dovetail ways e⁹ upon the side of the frame E. (See Figs. 1, 2, and 5.) Suitable movements are given the slide-block, and consequently the pawl, by means of the crank F on the shaft a³, the lever f, pivoted or having a fulcrum at f¹, (see Fig. 1,) and provided with three arms—namely, the arm f², which is connected by a connecting-bar, f², with the crank 8c F, the arm f³, which is connected with the slide-block e⁸, carrying the pawl, by the link f⁴, and the arm f⁵, which is connected by devices, hereinafter specified, to a clamping device adapted to be moved in the throat D. 85

The extent of the effective throw of the pawl is adjusted by means of the gib f⁶, (see Fig. 1,) which is held in the slide e⁸ in the guide-way e⁹ by means of screws f⁷ in a manner to be horizontally adjustable, and which also 90 has the inclined end f⁸, which projects in line with the movement of a pin, f⁹, on the feed-pawl e⁷. (See Fig. 1.) This pin is arranged so as to come in contact with the incline f⁸ upon the backward movement of 95 the pawl, and the time of engagement of the pawl with the tooth of the ratchet-wheel is determined by the position of this incline f⁸. If the gib f⁶ is set forward, then the effective stroke of the pawl is less. If it is set back, 100 the effective stroke is greater. The successive periods of movement and rest thus given to the block E bring each of its nail-receiving holes e successively in line with the throat D.

the holder being located so near the devices for pointing and severing the nail that the nails can be fed very rapidly to its holes, and also in a straight line.

5 To deliver the nails from the holder E into a different form than a circular one and in any arrangement for driving, I employ the stationary nail-distributing tubes G. Each tube has a passage of sufficient size to receive a nail 10 and permit it to pass freely through it. The tubes are held at their upper ends quite loosely in the enlarged holes g, formed in the under surface of the plate e³. (See Fig. 3.) The plate has perforations or holes formed in it in 15 said circular order as the nail-receiving holes e of the nail-holder E. The tubes are curved or bent to bring their lower ends into any desired arrangement in relation to each other, and they are held in such arrangement by 20 means of a plate, G', (see Fig. 3,) which has holes g' formed therein in the arrangement desired, and which are enlarged at their tops g² to receive and hold the lower ends of the tubes G. This plate is attached by a screw, 25 g³, to a downward extension of the stud e², and so as to be removable therefrom. The holes are of a size to quite loosely hold the tubes, and by removing the plate G' and substituting another plate having the same number of holes, 30 but bearing a different relation or arrangement to each other, the same tubes G may be used, or, if desired, the tubes G and the plates G' may be removed and other tubes G having other curves and another plate G' having a 35 different arrangement of holes may be substituted.

The distributor acts to receive nails from the holder E at the end of its rotation and to deliver them directly as a gang or group 40 through the holes g in any desired order or arrangement into a nail-carrier or perforated heel-blank or any other suitable receptacle.

In Figs. 2 and 6 I have represented a clearer, H, arranged to be moved into the throat or 45 passage D immediately below the converging point on the dies a a', and then downward therein to or very nearly to its lower end, then outward from the throat and upward to its original position, its office being to enter the 50 throat immediately after the making and delivery to the throat of a nail and to move downward vertically therein to push the nail from the throat into its appropriate nail-receiving hole in the holder E if it shall not have dropped sufficiently fast by gravity, or 55 if held back by friction or for any other cause. To enable this to be done, there is formed in the casing of the throat D a narrow vertical slit, d, of a width to receive the clearer H. 60 The clearer is arranged to project from the plate h, and it has an inclined upper edge, h'. (See Fig. 6.) The plate h has a roll, h², upon each side, which enters the vertical guiding-recess h³. The plate is moved vertically by 65 means of the connecting-rod h⁴, rock-lever h⁵, having two arms, one of which connects with the link h⁶ and the other with the link h⁷, ex-

tending to the lever f⁸. The link h⁴ is connected with the plate h at its corner h' and at one side of the rolls h², so that upon the downward movement of the plate, the rolls h² offering more resistance to the downward movement than to the swinging or turning movement thereon, the plate is first turned upon the rolls h² sufficiently to cause the clearer H to enter 70 the throat. The extent of this movement is limited by means of the arm h⁸, which is fixed to the end of the link h⁴ and the pin h⁹ on the plate. This relation of the parts will continue during the entire downward movement of the link h⁴—that is, the plate will be inclined to the link and the clearer will move downward in the throat. Upon the reverse movement of the link h⁴ exactly the opposite effect is produced—that is, the upward movement of the link h⁴ turns the plate upon the rolls h² to the 80 position shown in Fig. 6 and draws the clearer H from the throat. The extent of this movement is limited by the stop-bar h¹⁰ and pin h¹⁰ upon the plate, (see Fig. 6,) and the plate and 85 clearer bear this relation to the throat and link h⁴ during its upward movement.

The spring h¹¹, fastened to the link and to the frame of the machine, holds the link in proper relation to the rolls h² of the plate during its movement. 90

It will be seen that the clearer has practically four movements in the throat: first, an inward movement above the head of the nail; second, a downward movement to force the nail from the throat; third, an outward movement from the throat, opening it for the purpose of enabling the first nail in order to enter it, and, fourth, the upward movement to its original position. 105

The operation of the machine is as follows: The nails are made in successive order by the continuously-rotating pointing and severing dies. The nail-holder E is operated with an intermittent movement to bring each of its 110 holes in register with the throat of the machine. After each nail has been made and severed, the clearer H is moved inward and downward in the throat, and each hole of the holder is brought in register. The nail-holder 115 E is arranged as closely to the nail-making devices as possible, and is not much over the length of the longest nail which it is desired to make from them, so that each nail has but a short distance to travel to enter the holder, 120 and the clearer H also has a short movement. This insures two things: first, the sure feeding of each nail to its nail-receiving hole, and, second, great rapidity of action. After the last nail has been made and delivered, the nail-making devices come to rest, and the nail-holder is also stopped in position to deliver its 125 nails to the distributor. The start and stop motion mechanism is similar to that described in said Small application.

The holder E may have suitable friction applied to it for retarding its momentum at the end of the feed-stroke of the pawl.

The nail-hole-covering-plate of the holder E

is moved at the end of the movement of the block E to uncover the holes e, and the nails then drop as a gang from the nail-holder through the distributing-tubes to the nail-carrier G².

5 The nail-holder and distributor are removable from the machine, the frame of the machine having the recess F', (see Figs. 2, 5, and 7,) of a size and shape to receive the holder, and also having a shoulder, m, upon which the under surface of the plate e³ near its outer edge bears, (see Fig. 7,) and it may be held in place additionally in said position by a screw, button, or any other suitable locking device.

10 It is necessary to remove the block and distributor when the number of nails which it is desired to make vary; but it is only necessary to remove the pattern-plate G' and the tubes G when only the order or arrangement of the 15 holes is varied—that is, the order or arrangement upon which they are delivered from the distributor—while the number remains the same.

15 A machine of this construction has great capacity and accuracy and is cheaply made.

20 The nail-hole-covering plate e³ is shown in Figs. 5 and 8, and in Fig. 8 it is represented as having a projection, M'. This projection has an inclined edge which comes in contact with a stationary projection having an inclined edge as the block E approaches the end of its movement, which causes the plate e³ to be moved horizontally across the block E in opposition to the spring m', (shown in dotted lines in Fig. 25 5,) so that the holes of the plate e³ are brought in register with the holes e of the block E, and upon the forward movement of the block E the projection M' of the plate e³ passes or is moved by the stationary projection and permits the 30 spring m' to close the holes e by moving the plate to the position shown in Fig. 5.

Having thus fully described my invention, I claim and desire to secure by Letters Patent of the United States—

40 1. The combination, in a nail-distributing machine, of a throat through which nails are fed in successive order, a nail-holder, E, having a series of nail-receiving holes, e, arranged in circular order therein, and adapted to be brought successively into register with the throat D, a hole-covering plate attached to the block to be rotated therewith, and devices for imparting to said holder alternate periods of rotation and rest, substantially as described.

45 2. The combination, in a nail-distributing machine, of a throat through which nails are fed in consecutive order, a clearer movable vertically in said throat to move nails therefrom, a nail-holder, E, having the nail-receiving holes e and the hole-covering plate e³, and devices for imparting to said holder an inter-

rupted rotation to bring its nail-receiving holes successively in line with the throat, substantially as described.

3. The combination, in a distributing-machine, of a block, tube, or nozzle having a throat, D, and the rotary nail-holding block E, having the holes e, arranged in a circular line, with a distributor comprising the tubes G, having their upper ends arranged and held in a circular line and their lower ends arranged to deliver nails in any desired form or arrangement, as and for the purposes described. 65

4. The combination, in a distributing-machine, of the rotary nail-holding block E, having the holes e, arranged in a circular line, with a distributor comprising the tubes G, having their upper ends arranged and held in a circular line and their lower ends arranged to deliver nails in any desired form or arrangement, as and for the purposes described. 70

5. The combination of a distributor comprising the tubes G, holding-plate e³, having nail-receiving holes arranged in a circular order therein, the gage-plate G', and tube-receiving holes g², of any desired arrangement, and a rotary nail-holder arranged above the plate e³ and having nail-holding holes e, arranged in a circular line and adapted to register with the holes of the tubes G, and an interposed hole-closing device for closing the holes of the nail-holder and keeping them closed until it is desired to deliver the nails as a gang or group to the tubes of the distributor, substantially as described. 85

6. The combination, in a nail-distributing machine, of a tube, block, or nozzle having the throat D, the nail pointing and severing dies a a' C C', and the clearer H, substantially as described. 90

7. The combination of the nail-holder E, having nail-receiving holes e, the nail-covering plate e³, the ratchet-wheel e⁴, the feed-pawl e⁵, having the pin, and the pawl-adjusting plate having the inclined surface f⁸, substantially as described. 95

8. The distributor comprising the stationary plate or holder e³, having holes arranged in circular order, the tubes G, and the plate G', having tube-receiving holes of any desired order or arrangement, substantially as described. 100

9. The plate or tube holder e³, arranged to hold the upper ends of the tubes in a circular line or order, and the tubes G and the removable plate G', having tube-receiving holes of any desired order or arrangement, substantially as described. 105
